JOURNAL BOX LIFT

Filed Sept. 15, 1923

Inventor

B. Brannen.

By *Alfred J. Randolph Jr.*
Attorney

UNITED STATES PATENT OFFICE.

BERT BRANNEN, OF KEYSER, WEST VIRGINIA.

JOURNAL-BOX LIFT.

Application filed September 15, 1923. Serial No. 662,907.

To all whom it may concern:

Be it known that I, BERT BRANNEN, a citizen of the United States, residing at Keyser, in the county of Mineral and State of West Virginia, have invented certain new and useful Improvements in Journal-Box Lifts; and I do hereby declare the following to be a full, clear, and exact description of the invention, such as will enable others skilled in the art to which it appertains to make and use the same.

The object of the present invention is the provision of means whereby to facilitate the renewal of the brass or bearing of a car wheel journal. A further purpose of the invention is the provision of means whereby the wheel is prevented from rising during the lifting of the journal box to release the brass or bearing preliminary to replacement, said means utilizing the wheel as a rest for the fulcrum of the lifting bar.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is an end view illustrating the application of the invention, the dotted lines showing a car wheel and journal box and the full lines designating an ordinary lifting jack and the lifting means.

Figure 2 is a side view of the parts shown in Figure 1.

Figure 3 is a perspective view of a lifting bar.

Figure 4 is a perspective view of the block which is placed upon the lifting bar and engages the journal box, and

Figure 5 is a perspective view of the lifting bar fulcrum.

Corresponding and like parts are referred to in the following description and designated in the several views of the drawings by like reference characters.

The numeral 1 designates the lifting bar which may be of any determinate length and which usually consists of forged steel and which tapers slightly in length with its outer

end portion upwardly offset and formed in its under side with a notch 2 to engage the foot of any ordinary lifting jack employed in connection with railroads. A fulcrum 4 is fitted to a side of the lifting bar 1 adjacent its pivot end. The fulcrum 4 consists of a case-hardened bar of square form arranged to provide a knife-edge fulcrum which is adapted to engage the inner side of the rim or tread of a car wheel, as indicated most clearly in Figure 2. A steel block 5 is provided to rest upon the lifting bar a short distance from its pivot end and engage the journal box, whereby to lift the latter when the outer end of the lifting bar is moved upwardly by means of the jack 3 or in any other preferred and convenient way. It is observed that the pivot end of the lifting bar engaging the rim or tread of the wheel holds the latter down and prevents its rising when lifting the journal box to release the brass or bearing when it is required to renew the same. In its application, the lifting bar constitutes a lever of the second order.

What is claimed is:

1. A journal box lift consisting of a rigid elongated lifting bar, said lifting bar being operable as a lever of the second class and adjacent one end having substantially transversely disposed knife-edge fulcrum means engageable with the inner surface of a car wheel flange to anchor the lifting bar against displacement, said lifting bar extending outwardly beyond an engaged journal box and upwardly with respect to its fulcrum end to facilitate lifting.

2. A journal box lift consisting of a rigid elongated lifting bar, said lifting bar being operable as a lever of the second class and adjacent one end having substantially transversely disposed knife-edge fulcrum means engageable with the inner surface of a car wheel flange to anchor the lifting bar against displacement, said lifting bar extending outwardly beyond an engaged journal box and upwardly with respect to its fulcrum end and provided with a notch in its under surface to facilitate lifting.

In testimony whereof I affix my signature in presence of two witnesses.

BERT BRANNEN.
